UNITED STATES PATENT OFFICE

RALEIGH J. ADAMS, OF CHICAGO, ILLINOIS

BOILER

Application filed June 3, 1927. Serial No. 196,257.

My invention relates to boilers and particularly to boilers which are provided with means for superheating the steam generated therein.

6 A particular object of the invention is to provide improved superheater apparatus adapted to be built in a boiler as a component part thereof.

10 Many other objects and advantages of the construction herein shown and described will be obvious to those skilled in the art from the disclosure herein given.

15 To this end my invention consists in the novel construction, arrangement and combination of parts herein shown and described, and more particularly pointed out in the claims.

20 In the drawings, wherein like reference characters indicate like or corresponding parts:

Fig. 1 is a vertical longitudinal section taken from a boiler which embodies the invention;

25 Fig. 2 is a section taken on line 2—2 of Fig. 1;

Fig. 3 is a section taken on line 3—3 of Fig. 1; and

Fig. 4 is a section taken on line 4—4 of Fig. 1;

20 In the drawings, I have shown my invention embodied in a boiler of the type more fully shown and described in my copending application, Serial No. 116,856, filed June 18, 1926, but it is to be understood that I am limited to this construction only to the extent indicated in the appended claims.

35 In this instance, the boiler comprises a setting 1 which is provided with a combustion chamber 2. Disposed in the upper end of the setting 1 are steam and water drums 3 and 4, the drums 3 and 4 being positioned at substantially the same elevations and the drum 4 being positioned at the front of the setting. At 5, I have shown a mud drum which is positioned in the lower part of the setting 1 and is connected to the drums 3 and 4 through banks of tubes 6 and 7, respectively. Disposed intermediate the drums 3 and 4 and below them is a drum 8 which is connected by tubes 9 to the drum 4. The drums 5 and 8

communicate with each other through a bank of tubes 12 and through a bank of tubes 13. Positioned intermediate the tubes 12 and 13 and extending from the drum 5 to the drum 8 is a wall or baffle 14 and extending downwardly from the drum 3 to a point intermediate the drums 3 and 5 is a wall or baffle tile 15. I preferably provide a bank of tubes 17 in front of the baffle 15 which tubes 17 communicate with the drums 3 and 5. In the 60 illustrated embodiment of the invention, aligned baffles 17a and 17b insure that the gases of combustion will pass through the bank of tubes 12.

65 As set forth in my above-mentioned co-pending application, the drums 3, 5, 8 and 4 are so arranged that a relatively large number of tubes may be readily positioned there between so that the water may circulate freely through the boiler.

70 Water is admitted to the boiler through the pipe 35 which extends into the drum 3 and is adapted to discharge the water into a trough or pan 37 disposed within the drum. This construction is well known to those 75 skilled in the art.

75 Referring now to Fig. 1, it will be noted that I have provided a chamber 20 within the drum 4, the chamber 20 being formed by a substantially U-shaped wall 21. The chamber 20 does not communicate directly with the interior of the drum 4 but communicates through tubes with the drum 3 and with a header 24. Thus, I have shown a bank of tubes 26 which connect the chamber 20 with the header 24 and a bank of tubes 29 which connect the chamber 20 with the drum 3. It will be noted that the upper portions of the drums 3 and 4 communicate with each other through a bank of tubes 30 and that the upper portion of the drum 8 communicates with the upper portion of the drum 4 through two tubes 31, the tubes 31 being positioned at the ends of the drums. As best shown in Fig. 2, the header 24 extends through the side walls of the setting 1 so that steam may be withdrawn from either end thereof. It will be noted that the header 24 is disposed in the path of the heated gases of combustion, which flow around the edge of the baffle 17b.

As best shown in Figs. 1 and 4, the tubes 26 and 29 are preferably arranged in groups so that the ends thereof that project into the chamber 20 are accessible through handhole openings 39 provided in the wall 21. These openings are normally closed by plates 40.

The operation of the above described apparatus is substantially as follows:

Water is admitted to the boiler through the pipe 35 and circulates through out the drums and tubes. It flows upwardly in the tubes 7 and descends through the tubes 6 and 12. The steam generated in the drum 4 flows through the tubes 30 to the drum 3 and thence flows with the steam generated in the drum 3 through the tubes 29 to the chamber 20 after which it passes to the header 24 through the tubes 26. Steam generated in or collected by the drum 8 flows through the tubes 31 to the drum 4 and thence to the drum 3 by way of the tubes 30 which delivers it to the tubes 29. The tubes 26 and 29 function as a superheater as they are exposed to the gases of combustion which flow over the drum 8.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a boiler of the class described, a pair of drums, a plurality of baffles defining passes for gases of combustion, a header disposed in one of said passes, a chamber associated with one of said drums and sealed against communication therewith, tubes connecting said drums with each other, tubes connecting said chamber with the other of said drums than the one with which said chamber is associated, tubes connecting said chamber with said header, and means for withdrawing steam from said header.

2. In a boiler of the class described, a pair of drums, a plurality of baffles defining passes for gases of combustion, a header disposed in one of said passes and having its end extending through opposite walls of said boiler, a chamber associated with one of said drums and sealed against communication therewith, tubes connecting said drums with each other, tubes connecting said chamber with the other of said drums than the one with which said chamber is associated, tubes connecting said chamber with said header, and means for withdrawing steam from an end of said header.

In testimony whereof, I have hereunto signed my name.
